UNITED STATES PATENT OFFICE.

WALTER H. ZIMMERMAN, OF CHICAGO, ILLINOIS.

DAM CONSTRUCTION.

1,266,748.

Specification of Letters Patent. Patented May 21, 1918.

Application filed January 6, 1913. Serial No. 740,364.

To all whom it may concern:

Be it known that I, WALTER H. ZIMMERMAN, a citizen of the United States, residing at Chicago, in the county of Cook and State 5 of Illinois, have invented a certain new and useful Improvement in Dam Constructions, of which the following is a full, clear, concise, and exact description, reference being had to the accompanying drawings, forming 10 a part of this specification.

The object of my invention is to provide a dam construction by which the entire normal flow of water in the stream obstructed by the dam may be diverted through a secondary channel when desired without the 15 use of sluice ways or by-passes around the dam. By my invention I provide means in the construction of the dam itself which will accommodate the normal flow of the 20 stream so as to leave the dam site dry to facilitate the construction of the dam. The flow of water through the diverting means may be interrupted when the dam is completed, thus causing the water to accumulate 25 back of the dam. When for any reason it is desired to inspect the dam, the passageways through the diverting means may be again opened, thus presenting to view the entire 30 surface of the dam which is normally covered with water.

My invention also consists in the improved process of constructing dams involving the novel features outlined above. In building dams by my improved process the first thing 35 that is done is to put in place longitudinally of the stream a plurality of large diameter pipes which together shall have a sufficient capacity to accommodate the normal flow of water in the stream. These pipes are 40 preferably put in place with the aid of cribs at their ends which constitute the forms for constructing low coffer dams or auxiliary walls across the bed of the stream. When the walls and pipes are properly in place, 45 which may be accomplished without the use of the expensive auxiliary structure usually employed in erecting dams, the water flows through the pipes over the entire site of the dam, being discharged at the lower ends of 50 the pipes through the second coffer dam which serves to protect the site of the dam from water in the stream below the site. The dam is then constructed in precisely the same manner as though no water were flowing 55 in the stream at all, and after the dam is completed, by means of suitable gates in the

large pipes referred to, the flow through these pipes is stopped and the water is caused to accumulate back of the dam.

Other features of my invention consist in 60 an improved means for actuating the gates in the large pipes referred to, said means comprising a motor adapted to be brought into engagement with any desired one of the gates, thus reducing the amount of operating 65 mechanism to a minimum. Other features of my invention consist of a pumping system installed as a part of the dam construction by which any portion of the site of the dam may be pumped dry when desired. I also 70 provide a means by which a single over-head crane may be utilized through the entire length of the dam to carry repair parts or machinery into the interior of the dam structure, thus avoiding the necessity of having 75 a separate crane for each bay in which it is desired to handle such parts. A further feature of my invention consists in an improved means for operating an adjustable crest at the top of the dam, such crest being 80 formed in sections, any one of which may be engaged by a single operating mechanism, thus reducing to a minimum the cost of the operating device.

The several drawings illustrating my invention as are follows:

Fig. 1 is a longitudinal, vertical, sectional view through the completed dam showing the water levels for different conditions.

Fig. 2 is a view of the structure shown in Fig. 1 taken from the down stream side.

Fig. 3 is a detail sectional view of the sealing means employed around the large drain or sluice pipes where they pass through 95 the auxiliary walls and the dam itself.

Fig. 4 shows a detail view of the operating means employed in connection with the gates in the large drainage or sluice pipes.

Similar numerals refer to similar parts 100 throughout the several views.

As shown in Figs. 1 and 2 the dam construction includes a plurality of large pipes 1 made preferably of sheet metal riveted together and provided within the dam structure each with a gate 2. The pipes 1 and gates 2 are preferably assembled on the bank of the stream to be dammed and floated to place longitudinally of the stream so as to entirely cross the site selected for the dam. 110 Wooden forms are constructed around the ends of the pipes 1 and with the gates 2

open the pipes are sunk and concrete is filled into the forms at the ends of the pipes so as to form a transverse coffer dam 3 at the upstream ends of the pipes which extends entirely across the bed of the stream to form an auxiliary dam serving to back up the water sufficiently so that it will give head enough to drive all of the normal flow through the pipes 1. The down stream ends 10 of the pipes are similarly surrounded by a second, transverse coffer dam 4 which need only be high enough to protect the site of the dam from the tail water coming from the pipes 1, or the overflow during high water. 15 The site of the dam is then prepared in the manner usual in the art and the footing, 5 carefully laid to make as perfect a joint as possible with solid rock, after which the dam proper 6 is erected. The face portion 6 20 or main retaining wall of the dam is supported in a manner common in the art by means of buttresses 7 and is provided at the top with a horizontal portion 8 serving to deliver the overflow sufficiently to the rear of 25 the dam to protect the same from the action of the descending water. The buttresses 7 are reinforced by cross-beams 9 which are preferably of reinforced concrete construction as is the entire structure of the dam. 30 Where the pipes 1 go through the wall 3 a plurality of flanges 10 are riveted to the pipes to make a more perfect and water-proof joint than would be the case if the flanges were not employed. A similar construction is employed where the pipes extend through the dam 6. The space between the wall 3 and the dam face 6 is divided into a plurality of pockets by longitudinal walls 11 so as to facilitate the inspection of any 35 particular portion of the footing of the dam since all that is necessary is to pump the water from the pocket or section where the trouble is suspected, whereas without the walls 11 it would be necessary to pump out 40 all of the water trapped between the wall 3 and the dam in order to expose any particular part of the footing. 45 Inside of the dam structure, I provide a platform 12 extending transversely of the stream upon which a truck 13 is mounted upon suitable rails. The truck 13 as shown more clearly in Fig. 4, carries a motor 14 adapted to drive by bevel gears 15 and 16 one member of the jaw clutch 17 which may be moved vertically by means of the lever 18 50 pivoted to the truck frame at 19. The track supporting the truck 13 is so disposed upon the platform 12 that by moving the truck 13 the clutch member 17 may be brought into alinement with any one of a plurality of similar clutch members 20 secured to the upper ends of the gate shafts 21 by means of which the gates 2 are operated. Thus if it is desired to open or close any one 55 of the gates 2 the truck 13 is moved until the

clutch member 17 is brought into alinement with the particular clutch member 20 to be operated, for which position the lever 18 is operated to bring the clutch members 17 and 20 into engagement with each other. For 70 this condition, operation of the motor 14 will either open or close the desired gate 2 according to the direction of the motion of the motor.

In order to facilitate the construction of 75 the dam, I provide a track 22 just above the lower wall 4 upon which cars 23 may be run to deliver the parts of the dam or the machinery to be employed in connection with it at any point desired. Crane tracks 24 80 are provided in connection with each of the sections of the dam to which material may be required to be delivered and a traveling crane 25 adapted for use in connection with any set of tracks desired is shown which has connected with it a pair of eyes or rings 26 85 by means of which the crane may be lifted bodily from the tracks by the trolleys 27 and moved laterally of the stream upon the track 28 to any section desired. The track 28 is 90 supported by suitable brackets 29 from the buttresses 7.

At the top of the dam I provide a crest 95 comprising a plurality of adjustable sections 30 by means of which during high water the position of the overflow may be controlled. Each section 30 is hinged at its lower edge to the top of the dam construction and is provided with two operating rods 31, which, when the corresponding section is in vertical position, serve to lock the section in such position. A track 32 is provided below the lower ends of the rods 31, 100 which track extends transversely of the stream the whole length of the dam. Mounted upon the track 32 is a truck 33 provided with a pneumatic cylinder 34 by which a yoke 35 may be raised or lowered as desired. The yoke 35 is adapted to engage the lower 105 end of any pair of rods 31 when it is desired to operate the corresponding section 30 of the crest and in this manner by simple mechanism the entire crest may be controlled 110 as desired.

In connection with the dam construction 115 a piping system is installed consisting in a main pipe 36 extending the entire length of the dam from which at intervals, branches extend as shown at 37 controlled by suitable valves 38. The main pipe 36 is connected 120 with a pump adapted to remove the water from the pipe and from the portions of the dam foundation with which connection is established by the valves 38. Other branches 125 extend as shown at 39 through the dam 6 to the compartments, formed between the walls 11 which branches are controlled by individual valves 40. As a result of the construction above described, the entire under surface of the dam is available for in- 130

spection at all times and water may be pumped from any of such sections by operating suitable ones of the valves 38. At any time it is desirable to inspect the upstream surface 6 of the dam the gates 2 are opened by means of the motor 14 for which condition the entire flow of water is taken care of by the pipes 1 and then any one of the compartments formed by the walls 11 5 may be pumped out by opening the corresponding valve 40 connected with the branch pipe 39 extending to the particular compartment. In this way any part of the dam construction may be examined when required 10 without the use of expensive temporary coffer dams or caissons to protect the dam from the flow of water. It is to be borne in mind that since the wall 3 is normally entirely covered with water, practically no 15 strain is exerted upon it and therefore that when properly constructed such wall will last indefinitely. The dam 6, however, is subjected to the entire head of water when the water above the dam is backed up to its 20 maximum depth and thus, notwithstanding the most careful construction, trouble may develop along the footing or some other part of the inclined portion of the dam which would easily result in serious damage if the 25 pressure of water could not readily be removed. The buttresses 7 form together with the face 6 and the wall 4 separate compartments which may be pumped out individually as desired so as to determine whether 30 there is any leak around the footing 5 in connection with any particular one of the compartments thus formed. In this way the development of leaks may be accurately kept track of and they may be checked before 35 they have progressed to a point seriously endangering the dam construction. A platform 41 extending the length of the dam is provided to give access to the valves 38 and 40. 40 From the above it will be understood that my invention is of value in a number of different combinations, that is to say, the upper and lower auxiliary walls together with the large pipes extending between them are 45 extremely useful in connection with the construction of the main portion of the dam. Again, in certain cases the lower retaining wall may be done away with if the flow of water is comparatively small or the drop 50 in the bed of the stream is sufficient to take care of the water flowing from the large 55

pipes without the use of a retaining wall to protect the site upon which the dam is to be built. After the main structure of the dam has been completed the pipes serve their purpose in connection with the upper auxiliary retaining wall whether the lower retaining wall is employed or not since the water may be diverted through the pipes and under the dam as effectively one way as 60 the other, and thus the entire outer surface of the main retaining wall of the dam may be inspected if desired with either arrangement. If, however, it is also desired to inspect the site of the dam it will generally be 65 found necessary to employ the lower auxiliary retaining wall so that the compartments formed between the main retaining wall of the dam and the lower retaining wall by the buttresses may be pumped dry. 70

75 While I have shown my invention in the particular embodiments described, I do not, however, limit myself to this arrangement, but desire to claim broadly any equivalent that may suggest itself to those skilled in the art.

What I claim is:

1. In a dam construction, the combination of a main retaining wall for the water to be stored, an auxiliary retaining wall 85 above the main retaining wall, a second auxiliary retaining wall below the main retaining wall, and a large diameter pipe or pipes extending from one auxiliary retaining wall to the other through the main retaining wall 90 to conduct the water from above the upper retaining wall below the lower retaining wall.
2. In a dam construction, the combination of a main retaining wall for the water to 95 be stored, an auxiliary retaining wall above the main retaining wall, a second auxiliary retaining wall below the main retaining wall, a large diameter pipe or pipes extending from one auxiliary retaining wall to the 100 other through the main retaining wall to conduct the water from above the upper retaining wall below the lower retaining wall, and a gate valve in each of said pipes.

In witness whereof, I hereunto subscribe 105 my name this 15th day of August, A. D. 1912.

WALTER H. ZIMMERMAN.
